PULL FOR DRAWERS, DOORS, AND THE LIKE

Richard C. Massen, 2180 Catalina, Laguna Beach, Calif.

Filed Feb. 25, 1963, Ser. No. 73,696

Term of patent 14 years

(Cl. D10—8)

FIGURE 1 is a front perspective view of a pull for drawers, doors, and the like embodying my new design;

FIGURE 2 is a front elevational view thereof;

FIGURE 3 is a rear elevational view thereof;

FIGURE 4 is a side elevational view taken from the left of FIGURE 1 thereof; and

FIGURE 5 is a front perspective view of a modified form of a pull for drawers, doors, and the like wherein the lateral inserts between the flanges are omitted.

The broken-line showing of a pair of screws threaded into the internally-serrated slot on the rear of the pull for drawers, doors, and the like in FIGURES 1, 4 and 5 is for illustrative purposes only.

I claim:

The ornamental design for a pull for drawers, doors, and the like, substantially as shown and described.
